ATTORNEY

UNITED STATES PATENT OFFICE.

ETHEL LARIMORE, OF BARBERTON, AND VIOLET FRAME, OF AKRON, OHIO.

GARTER.

Application filed September 25, 1925. Serial No. 50,016.

To all whom it may concern:

Be it known that we, ETHEL LARIMORE and VIOLET FRAME, citizens of the United States, residing at Barberton and Akron, respectively, in the county of Summit and State of Ohio, have invented new and useful Improvements in Garters, of which the following is a specification.

This invention relates to garters, the general object of the invention being to provide a tubular member which is formed of resilient material and is of ring shape and of considerable diameter so that stockings or socks can have their tops rolled around the garters to give the rolled effect now in fashion.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:—

Figure 1 is a view showing the garters in use.

Figure 2 is a view of the garter.

Figure 3 is a section on line 3—3 of Figure 2.

Figure 4 is a sectional view showing the manner of connecting together the ends of the tube.

As shown in these views, the garter 1 is formed of a tube of flexible material, such as rubber, with one end overlapping the other end, as shown at 2, so that the tube

forms a ring shaped member. This tube is inflated to an extent where it will be of circular formation in cross section and will not collapse when the top of the sock or stocking is rolled around the same.

Thus an elastic garter is produced which will give the top of the stocking the rolled effect desired.

The garter is flexible throughout its length, which will cause the garter to accommodate itself to the contour of the leg and will facilitate the rolling of the stocking around the garter.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:—

1. A garter for forming a roll at the top of a stocking, comprising a tube having its ends connected together to form a ring-shaped member with the tube inflated sufficiently to prevent it from collapsing, and the garter being flexible throughout its length.

2. A garter for forming a roll at the top of a stocking, comprising a tube of resilient material having its ends fastened together by one end being drawn over the other, said tube being inflated to a sufficient extent to prevent it from collapsing and the garter being flexible throughout its length.

In testimony whereof we affix our signatures.

ETHEL LARIMORE.
VIOLET FRAME.
